KITE

John L. Koonce, Rte. 1, Box 121, Taft, Tex.

Filed Feb. 8, 1963, Ser. No. 73,485

Term of patent 14 years

(Cl. D34—15)

FIG. 1 is a perspective view of the underside of a kite embodying my design; and

FIG. 2 is a perspective view of the top side of the kite of FIG. 1.

This application is a continuation-in-part of my earlier application, Serial No. 67,647, filed November 22, 1961, entitled "Kite," and now abandoned.

I claim:

The ornamental design for a kite, substantially as shown and described.
